Patented June 9, 1925.

UNITED STATES PATENT OFFICE.

HECTOR M. BAXTER, OF BATTLE CREEK, IOWA.

SNOW FENCE.

Application filed July 1, 1924. Serial No. 723,462.

To all whom it may concern:

Be it known that I, HECTOR M. BAXTER, a citizen of the United States, and a resident of Battle Creek, in the county of Ida 5 and State of Iowa, have invented certain new and useful Improvements in Snow Fences, of which the following is a specification.

An object of my invention is to provide a 10 fence construction to be used at the side of a highway for preventing snow drifting onto the road.

A further object is to provide such a fence which is of the cheapest and simplest possible construction, and yet is durable and, when properly positioned, will stop the course of snow carried by the usual northwest wind, and cause it to drift on the windward side of the fence.

20 A still further object is to provide a fence which will not present such resistance to the wind as would be offered by a solid fence, but will allow air currents to pass through, while stopping the drifting of snow.

25 With these and other objects in view, my invention consist in the construction, arrangement and combination of the various parts of my device, whereby the objects contemplated are attained, as hereinafter 30 more fully set forth, pointed out in my claims, and illustrated in the accompanying drawings, in which:

Fig. 1 is a perspective view of a portion of a road, with my improved fencing installed on one side thereof.

Fig. 2 is a sectional view through a portion of the fence, diagrammatically illustrating the effect upon snow laden air currents, of the fence.

40 Since paved highways have become numerous and much used in interstate travel, the necessity of keeping them free of drifted snow in the winter time has presented itself. Especially in the prairie sections of 45 the country does this problem become serious, since there the snow is carried for many miles along the surface of the ground, by the wind, and is deposited in every depression and hollow, in drifts. The ordinary highway is flanked at many points by embankments where cuts have been made, and the snow often deposits to great depths in these cuts.

45 The problem has been approached by the 50 providing of solid fences along the windward side of the road, but there are certain

objections to such device which my invention is designed to eliminate.

The solid fence stops the current of air almost entirely, and the wind is thereby deflected upwardly over the fence. A certain amount of the snow will be caught in the dead air pocket formed on the windward side of such a fence, but much of it will be carried on over the fence by the wind and deposited in the road.

55 It will be understood that the greater quantity of the drifting snow is carried at a level only a few inches from the ground.

60 My invention contemplates the interposing of a permeable element in the path of the wind, which will allow the air currents to pass through itself to such an extent that the air currents will not be deflected upwardly, and will at the same time check the 65 drifting snow carried close to the ground, and cause it to be heaped up on the windward side of the fence.

70 In the drawings, I have used the reference character, 10, to indicate the bed of a road.

75 My fencing is formed of slats, 11, connected by wires or other means, 12. The fencing may be installed by nailing to posts, 13.

80 Each slat has the side faces, 14, and the inclined faces, 15. The faces, 15, are disposed at angles of approximately 45° to the sides, 14. The spaces between the slats are such that the fence, when viewed from an angle perpendicular to the faces, 15, presents an unbroken appearance.

85 The utility of my device relies on the fact that 95% of the snowstorms are carried by a northwest wind. In installing the device, the slats are positioned so that the inclined faces are perpendicular to this northwest direction.

90 As the air currents, travelling as indicated by the arrows, 16, strike the inclined faces, they are deflected, as at 17, and a portion thereof will create a current of air parallel to the front and rear faces of the slats, as indicated by the arrows, 18. The large portion of the air currents will continue on in the direction of the arrows, 19.

95 The rapid movement of the air past the windward acute corner of each slat (indicated on the drawings at 20), will tend to create a partial vacuum adjacent the inclined face adjoining that corner, and, aided by the transverse current at 18, a portion of the air will be deflected back between the 100 105 110 115

slats as at 21, producing a whirling motion of the air between the slats which opposes the movement of the snow flakes through the fence and causes them to be deposited substantially as indicated; to pile up against the windward inclined face of the next adjacent slat.

It will be understood that a portion of the snow flakes will be deflected and carried 10 on through the fence, but that the mass and inflexibility of the snow particles will cause most of them to be deposited against the windward inclined faces of the slats.

The effectiveness of the device is aided by 15 the fact that snow particles will ordinarily adhere to a surface against which they impact with sufficient force. This may be attributed to the heat, caused by the impact, momentarily melting the surface of the 20 snow flake sufficiently to cause it to instantly freeze when the force of the impact is expended.

I have tested out a section of fencing constructed according to my invention, and 25 have found that it is effective in every case, where the wind is substantially from the northwest, in stopping the drifting snow.

It will be remembered that the mass of the drifting snow is carried very near the 30 ground and that it is sufficiently dense to be readily trapped by the counter currents set up between the slats. The volume of the air current passes through the slats above the point where the snow is being 35 trapped, and as the level of the snow increases the air currents will be correspondingly shifted upwardly.

Some changes may be made in the construction and arrangement of the parts of my invention without departing from the 40 real spirit and purpose of my invention, and it is my intention to cover by my claims, any modified forms of structure or use of mechanical equivalents which may be reasonably included within their scope. 45

I claim as my invention:

1. In a snow retaining fence, a series of spaced upright slats, each slat being substantially parallelogram-shaped in cross section, the lateral faces of the slats being inclined relative to the front and rear faces, the slats being so spaced that a plane passing through an acute corner of one slat perpendicular to the lateral faces of the slat will intersect the adjacent acute 55 corner of an adjacent slat.

2. In a snow retaining fence, a series of spaced upright slats, substantially parallelogram-shaped in cross section, the lateral faces of the slats being inclined at a substantial angle to the plane of the fence when disposed in erected position, and the slats being spaced a distance approximately equal to the width of a face of a slat.

3. In a snow retaining fence, a series of 65 spaced upright slats, the lateral faces of the slats being inclined relative to the front and rear faces and being substantially parallel to each other.

Signed at Battle Creek, in the county of 70 Ida and State of Iowa, this 24th day of June, 1924.

HECTOR M. BAXTER.
